UNITED STATES PATENT OFFICE.

JOHN HUMPHRYES, JR., OF MANSFIELD, OHIO.

PUMP.

SPECIFICATION forming part of Letters Patent No. 336,857, dated February 23, 1886.

Application filed December 3, 1885. Serial No. 184,590. (No model.)

To all whom it may concern:

Be it known that I, JOHN HUMPHRYES, Jr., of Mansfield, in the county of Richland and State of Ohio, have invented certain new and 5 useful Improvements in Pumps; and I do hereby declare the following to be a full, clear, and exact description of the invention, such as will enable others skilled in the art to which it pertains to make and use the same.

10 My invention relates to improvements in pumps in which a round pump-rod of uniform size is employed with a sleeve mounted thereon and adjustably secured to the rod, said sleeve having one or more ears, to which 15 latter is pivoted the pump-handle, the object being to improve the construction and reduce the initial cost of the pump.

Heretofore with the better class of pumps, where a guide was employed for the upper 20 end of the pump-rod, the upper portion of the latter was usually enlarged and made square or rectangular in cross-section, with a hole through the enlarged portion for receiving the bolts for pivoting the handle to the 25 rod. Such pump-rods were expensive to make.

Since the advent of cold rolled or drawn shafting and rods it is found that such rods of suitable size make excellent pump-rods, and 30 require no fitting, except to cut them in suitable lengths and attach the respective rods to the pump plunger or piston. I have therefore devised a sleeve and attachment for connecting the pump-handle with the pump-rod, 35 by means of which construction a considerable saving is effected in the initial cost of the pump.

In the accompanying drawings, Figure 1 is a view in perspective of a pump embodying 40 my invention. Figs. 2 and 3 are enlarged views in perspective of sleeves that are respectively mounted on the pump-rod for attaching the handle.

A represents the body of the pump, that 45 may be of any desired form.

B is the cover, with a stuffing-box, b, through which the pump-rod C passes. The cover B has an upwardly-projecting arm, B', the latter having a slot, b', for the passage of the 50 handle D, and a laterally-projecting head, b'',

the latter having a vertical hole, through which the rod C passes and is guided thereby.

The rod C may be made of any suitable material; but round rods of cold rolled or drawn iron are well adapted for these pump-rods, 55 and require no labor, except to cut the bars into suitable lengths and fit the respective rods to the piston or plunger of the pump.

For attaching the handle I employ a sleeve, E, that embraces the piston-rod, and has one 60 or more ears, e, for pivoting the handle.

In Fig. 3 a sleeve is shown having one ear, and the handle is consequently made forked to embrace the ear. This sleeve is secured on the pump-rod by means of the set-screw e'. 65

In Fig. 2 the sleeve has two ears between which the end of the pump-rod enters. With this latter construction, in place of the set-screw for fastening the sleeve, a slot, e'', may be "cast in," or milled, if preferred, in which 70 case the sleeve is clamped to the pump-rod by tightening the pivotal bolt F. If the bore of the sleeve approximately fits the pump-rod, there will be no difficulty in clamping a cast-iron sleeve to the pump-rod as aforesaid. 75

The bore of the sleeve can usually be cast with sufficient accuracy; if not, but slight reaming is required to fit the bore. The handle prevents the pump-rod from turning, if there be any such tendency. The handle is 80 pivoted at d to the swinging fulcrum G, the latter being pivoted at g, as shown.

A round pump-rod of uniform size, together with the sleeve, can be made at a considerable reduction in the initial cost on a pump-rod having a square or rectangular or enlarged portion. 85

In assembling the parts the sleeve is easily adjusted on the pump-rod to give the proper sweep to the handle, and can be changed at 90 any time to bring the handle at a convenient height for the operator.

Any suitable connection may be made with the upper end of the rod C when it is desired to operate the pump by a wind-wheel or other 95 power.

What I claim is—

In a pump, the combination, with a pump-rod made round in cross-section and of uniform size, of a sleeve formed in a single piece and 100

mounted on the pump-rod, said sleeve having ears for embracing the end of the pump-handle, and an elongated slot, substantially as described, between said ears, the parts arranged substantially as indicated, whereby the sleeve is clamped on the pump-rod by tightening the pivotal bolt that connects the handle, substantially as described.

In testimony whereof I sign this specification, in the presence of two witnesses, this 10
16th day of November, 1885.

JOHN HUMPHRYES, JR.
